LOUIS BELL AND NORMAN MARSHALL, OF WEST NEWTON, MASSACHUSETTS.

METHOD OF AND APPARATUS FOR UTILIZATION OF OBSERVABLE RADIATIONS.

1,385,657.

Specification of Letters Patent. Patented July 26, 1921.

Application filed March 4, 1918. Serial No. 220,329.

To all whom it may concern:

Be it known that we, LOUIS BELL and NORMAN MARSHALL, citizens of the United States, residing at West Newton, county of 5 Middlesex, Commonwealth of Massachusetts, have invented certain new and useful Improvements in Methods of and Apparatus for Utilization of Observable Radiations, of which the following is a specification.

10 This invention relates to signaling, observation and the like by rays ordinarily invisible and is especially adapted for use in war where operations are being conducted in the presence of the enemy.

15 Our invention can be used at sea or in the trenches for visual or other signals which may be recorded in any manner well known to those skilled in the art, without danger of enemy discovery, and is capable of embodiment in devices easily portable and compactly made from readily procurable materials.

20 Our invention is founded upon the fact that there are radiations from a source of high temperature such as an arc or incandescent lamp at either side of the visible part of the spectrum, that is, of shorter and longer wave lengths than the visible spectrum. The radiations at either side of the 25 visible spectrum while invisible themselves, follow generally the laws of reflection and refraction of visible light, and produce various fluorescent, chemical, electrical, and other physical effects which can be detected 30 by suitable receiving apparatus.

35 In carrying out our invention we project a beam of such rays to a distant point where it is collected, reflected or refracted for observation.

40 The method of practising our invention and some convenient forms of apparatus will be more fully set forth in the specification which follows, and the same are illustrated in the accompanying drawings to which reference is made.

45 Figure 1 is a somewhat diagrammatic view of sending and receiving apparatus in accordance with our invention.

50 Fig. 2 is a sectional view of a receiving telescope for use in observation and signaling.

Fig. 3 is a sectional detail of an observing eye piece therefor.

Fig. 4 illustrates the use of a photo-electric cell as a receiving device for such a set. 55

Figs. 5 and 6 are diagrammatic views similar to Fig. 1, but illustrating the principles of our inventions as applied to observation alone.

Fig. 7 is a face view of a field signal set. 60

Figs. 8 and 9 are plan and end views, respectively, of the same, and

Fig. 10 is a diagrammatic view illustrating the recording of signals by photography. 65

There have been many difficulties in the utilization of radiation which by our invention have been avoided or overcome. Such difficulties are, for instance, the obtaining of a beam of suitable intensity from a source practicable for use in the functions heretofore stated; in the difficulty of providing receiving apparatus of sufficient sensitiveness without being at the same time easily disarranged and uncertain of function; and above all providing both sending and receiving apparatus sufficiently portable for the practical operation of observation and signaling. 70

Many substances are extremely opaque to invisible rays or reflect them badly, and others, which are free from these difficulties, are practically unobtainable or unusable on a practical scale. For instance, quartz and fluorspar are notoriously transparent to ultra-violet, but neither of them can be had readily enough or in pieces of sufficient size 75 to render their use practicable. Rock salt, the substance most commonly used in the infra red portions of spectra on account of its great permeability to such rays, is extremely sensitive to moisture, and hence out 80 of the question for military purposes. 85

To certain groups of invisible rays, which might otherwise be desirable, glass is quite opaque, and with certain others, reflecting substances are undesirable because they absorb badly. Moreover, certain groups of 90

rays in themselves are undesirable for practical use because they are quickly absorbed by the atmosphere, or are obtainable in quantity only from sources not convenient 95 for general use. We have found therefore that each range of invisible rays presents its 100

specific difficulty in generation, selection, sending and reception, and it is the object of our invention to adapt each to each so as to produce a method and apparatus for the utilization of invisible radiation of a simple, practical and efficient character.

The beam whether direct or reflected should be suitably concentrated by reflection or refraction and may then be received upon devices possessing high sensitiveness with respect to the particular group of radiations concerned. It may for instance be received upon a fluorescent screen and thereby made immediately optically visible, or upon any of the well known forms of photo-electric detectors, rendering it detectable by its electric effects.

We have contemplated three general forms of practice of our invention:

20 First, such an invisible beam may be directed on sea or land for the purpose of signaling orders or directions by interruption of the beam in accordance with a predetermined code. This end may be effected by 25 a suitable receiving apparatus at the distant station and the latter may signal back either by a similar sending apparatus or by suitable interception of the received beam reflected from an appropriate surface.

30 We have found that, particularly for signaling purposes, a large part of the invisible range of radiation is ill adapted for one or the other of the reasons here suggested, and our preferred range of radiation for this 35 purpose consists in those radiations lying between $400 \mu\mu$ and $350 \mu\mu$ wave lengths, which are just too short to be ordinarily visible to the human eye, and yet not short enough to be suppressed by ordinary refracting or reflecting media.

40 Second, such an invisible beam may be turned upon an object, as for instance a friendly ship, provided with diffused or spectral reflecting surfaces by which the 45 beam may be turned back and observed, so as to recognize the nature and position of the reflecting surface in order to preserve its identity or secure its suitable alinement, as in squadron formation.

50 Finally, the detection by means of the invisible rays of objects otherwise invisible at night. This may be accomplished by what is practically a searchlight of invisible rays, the portion of the beam reflected being 55 picked up again at or near the sending point by suitable receiving apparatus. This may apply even to rendering visible objects like an enemy's ship, otherwise indistinguishable, and to which the presence of a searching 60 beam must not be disclosed.

The group of radiations here referred to is relatively easy to isolate in practical quantity, since it can be screened out from the rest of the spectrum by suitable color 65 screens of relatively simple character.

We do not confine ourselves to obtaining a beam solely by the use of color screens, since radiations may also be isolated by selective total reflection or by taking advantage of the fact that the focal length of a 70 given lens is materially less for these rays than for the visible spectrum, and hence a small aperture placed at the proper focal point will let through freely a beam of invisible light while blocking nearly all the 75 visible light, a method which is already familiar to investigators.

Furthermore, and of great practical importance, we find by experience that this particular range of radiations is easily obtainable from incandescent electric lamps or a similar incandescent source, giving a source of energy at once steady, efficient and convenient, and particularly adaptable to portable use. Experimental work on ultra violet 80 radiations has been heretofore confined almost exclusively to sources specially rich in extreme ultra violet, sources such as highly specialized electric arcs, involving the use of iron or other metallic terminals, or by 85 use of such sources as vacuum tubes and mercury arcs, possessing the same characteristics. These sources are none of them convenient for field use; most of them are unsteady and require the use of highly specialized 90 electrical sources involving voltage not readily obtainable of sufficient strength in portable appliances.

The specified group of radiations which we prefer to use is free from these objections and is of extremely low visibility. A concentrated beam of this character is completely invisible in its passage through the air, and invisible also to direct view beyond extremely short distances, compared 105 with that at which it may be detected by means which we have provided and that meet all the practical requirements of an invisible signaling apparatus. In receiving such a beam, it can be concentrated through 110 glass lenses without serious loss of intensity, even non-achromatic lenses being suitable on account of the comparatively narrow range of wave lengths.

The fluorescent eye-pieces as applied to 115 spectrosopes in which the beam is spread out on a prism has long been known, but so far as we are aware no attempt has been made to produce a concentrated fluorescent image upon a fluorescent screen of any kind 120 or adapted for purposes herein described.

Suitable fluorescent screens may be made of uranyl sulfate or barium platinum cyanide, the greenish fluorescence of which is characteristic and well known. We believe, 125 however, it has not heretofore been recognized that the greenish fluorescence, other things being equal, is of higher visibility and is therefore of peculiar utility in use in accordance with our invention. Such 130

screens therefore combine in their fluorescent efficiency with the low visible beam employed in our system.

We have discovered moreover that the 5 most reliable and sensitive fluorescent screens are radically different from those heretofore used in fluorescent eye pieces. We prefer to employ for the purpose translucent or opaque films of material giving a 10 greenish fluorescence when in a solid condition. We therefore use a translucent film of such material deposited on some transparent material and viewed from the rear or compacted into an opaque screen and viewed 15 from the front upon which the light falls.

In order to make more clear the actual 20 practice of our invention we have shown in the drawing somewhat diagrammatically certain of the means for practising our invention, and more in detail certain of the actual 25 apparatus as adapted for field use.

Referring to Fig. 1, we have indicated at 30 A a projector which preferably is in the form of a search light having a source of light a, reflector b, and a selective screen c. Each projector is in usual practice accompanied by a receiver which is preferably in the form of an observing telescope with an objective d, screen e, and eye piece f, all as 35 appears in Fig. 1.

The beam projected from A by suitable 40 predetermined alinement with the receiver B at a point to which the signal is to be delivered is selectively screened by c. These 45 rays are substantially invisible to the eye but in falling upon the screen e cause the same to fluoresce. This fluorescence is observed through the eye piece f.

If now the beam from the projector A 45 is interrupted in accordance with a predetermined code a signal may be received as a message. The receiving telescope is shown somewhat more in detail in Fig. 2, in which the light is reflected from the mirror g on to the fluorescent screen e from which it is observed by the eye piece f.

In Fig. 3 we have shown a detailed modification whereby any telescope may be fitted 50 as a receiving device in accordance with our invention. It contains the fluorescent screen e¹ which is observed with the eye lens f¹ and the field lens f². The field lens may of course be omitted or any other familiar form of eye piece substituted for it, provided the 55 screen e¹ is in the principal focus of the telescope for the chosen range of invisible rays, and in the focus of the eye piece for the rays of fluorescence.

Instead of employing an optical receiver 60 such as we have just described and suggested, we may in some instances employ a photo-electric cell as a receiving device as indicated in Fig. 4.

In such a device the invisible rays are

concentrated by a mirror D on a glass bulb 65 i carried on an adjusting stem h which may be conveniently passed through an aperture in the center of the mirror. We have indicated at j the focus of the mirror D, a photo-electric sensitive layer of any suitable metal 70 or alloy, close in front of which is supported an open work grid k of metal forming the other terminal. From the terminals j and k lead wires l and l¹ are taken in circuit with the battery m to any convenient device sensitive to minute currents, as for example the galvanometer n.

The signal message may also be received 75 (and recorded) by the successive exposure of a suitable sensitized film upon which the successive signal images are photographed, as shown in Fig. 10.

Before considering the preferred detail construction of our field projecting equipment, attention may be directed to the matter of observation of an object by night by means of the invisible rays projected in accordance with our invention.

In Figs. 5 and 6, we have indicated diagrammatically the use of a projector A, as 90 shown in Fig. 1. We have indicated at C an object reflecting the invisible rays, which reflection is received, collected and observed by the telescope B or other suitable device in accordance with our invention. If the 95 object C is for example a friendly ship, a most advantageous observation may be had by providing it with a reflecting surface c¹ which may be convex in order to widen the field and facilitate the observation. The reflecting surface c¹ may furthermore be constituted a signaling device by providing means for covering it or uncovering it with a nonreflecting surface so that an operator at C can signal back by the same projected beam by which he has observed. The reflecting surface c¹ may be covered by any 100 opaque object such as a hand screen (not shown).

This feature of our invention is capable of 110 a very great variety of applications in both marine and land operations. At sea it may be employed not only for the detection of hostile ships but enables friendly ships to keep track of the position of each other as well as to signal as to position or course.

It is of course not possible in the scope of the specification to detail all uses and variety of circumstances under which our device may be employed, and in fact it is believed that 120 many uses not at present thought of will be developed in the service by those skilled in the departments in which our invention may be employed.

While our invention is capable of many 125 embodiments and a great variety of adaptations to devices already in use, we have provided for immediate service a convenient

portable device well adapted to military usage which we have illustrated in Figs. 7, 8 and 9. In these figures we provide a case P containing suitable batteries and conveniently carried by a sling Q. A light source preferably in the form of a search-light R having suitable screen S is mounted with universal connection T on the box P. We provide at U a suitable telegraph key by which the circuit of the lamp R may be interrupted by breaking the circuit or by shunting, whichever may be desired, or the front of the lamp A may be screened by perfectly opaque shutters V. For convenience in sighting, a telescopic or other sight W may be mounted on the lamp provided with suitable cross wires w, or other device, for effecting accurate alinement of the lamp R with the receiving device. The lamp R is preferably so mounted on the box P that it may be turned down into a protective recess therein or a suitable cover not shown may be hinged to the box top.

The apparatus herein shown and described may be variously modified and other forms of apparatus may be used in the practice of our invention. Furthermore, considerable latitude in ray selection may be practised and our invention may be variously utilized as the changing conditions of modern warfare dictate, all without departing from the spirit of our invention if within the limits of the appended claims.

What we therefore claim and desire to secure by Letters Patent is:

1. A method of signaling which consists in isolating from a suitable source radiations lying between 400 $\mu\mu$ and 350 $\mu\mu$ causing them to be formed into a directed beam, concentrating said beam, and detecting said beam by means of a fluorescent medium and interrupting said beam in accordance with a predetermined code.

2. The method of signaling which consists in forming a radiant beam, isolating from it radiations lying between wave lengths 400 $\mu\mu$ and 350 $\mu\mu$, receiving and focusing said beam upon a medium fluorescing greenish in said rays, and interrupting said beam in accordance with a predetermined code.

3. In combination for the purpose set forth, an incandescent electric lamp, a reflector to form a beam of the radiation therefrom, means of selecting from said beam radiations between wave lengths 400 $\mu\mu$ and 350 $\mu\mu$, means for concentrating said radiations upon a greenish-fluorescing screen sensitive thereto, and means for establishing, varying and interrupting said beam in accordance with a predetermined code.

4. For the purpose set forth, a source of light, means for producing a concentrated beam of radiations therefrom, screens selectively absorbing the ordinarily visible spectrum while transmitting radiation of wave

lengths lying between 400 $\mu\mu$ and 350 $\mu\mu$, means for concentrating into a focus said radiations at the point of reception and means adapted to detect the presence of such radiation placed at said focus.

5. In combination for the purpose set forth, an incandescent body of high temperature furnished with a reflector having a mouth, a screen closing the mouth of said reflector, and transmitting radiation of wave lengths between 400 $\mu\mu$ and 350 $\mu\mu$ while opaque to the ordinary visible spectrum, means for interrupting said radiation in accordance with a predetermined code and a receiving telescope having a greenish-fluorescing screen in its focus.

6. In combination for the purpose set forth, an incandescent body of high temperature furnished with a reflector having a mouth, a screen closing the mouth of said reflector and transmitting radiation of wave lengths between 400 $\mu\mu$ and 350 $\mu\mu$ while opaque to the ordinary visible spectrum, means for interrupting said radiation in accordance with a predetermined code and a receiving telescope having a fluorescing screen in its focus, with a translucent film of solid fluorescing material in the focus of the objective for the rays specified and in the focus of the eye piece for green rays.

7. A method of utilizing invisible light rays, consisting in forming a directed beam of rays between 400 $\mu\mu$ and 350 $\mu\mu$ wave length and collecting said rays for observation on a fluorescent medium.

8. A method of signaling consisting in forming a directed beam of rays from within in the limits of a narrow spectrum band situated between the limit of visibility and vitreous absorption, focusing said rays and detecting said focal point by its effect in exciting fluorescence.

9. In a signal apparatus, a transmitter including means for projecting a directed beam of rays from that band in the ultra violet zone lying next adjacent the visible spectrum, and a receiver including a screen having a greenish fluorescence under said rays.

10. A method of utilizing invisible light rays for signaling or the like, consisting in forming a directed beam of rays of from 400 $\mu\mu$ to 350 $\mu\mu$ wave lengths and in focusing said rays for observation on a fluorescent medium.

11. In a signal system, a source of radiant energy having a vitreous inclosure, a vitreous ray filter transmitting rays only between 400 $\mu\mu$ and 350 $\mu\mu$, a projector for directing the light in a beam, a control for interrupting the light, an image receiving screen having a responsive fluorescence of greenish character, a lens for focusing the received beam on said screen and an eye piece for observing said screen.

12. In a signal system, a source of radiant energy having a vitreous inclosure, a vitreous screen permeable to rays of wave length in the region between 400 $\mu\mu$ and 350 $\mu\mu$ but 5 opaque to the blue end of the visible spectrum, a projector for directing the light in a beam through said screen, a control for interrupting the light, an image receiving screen having responsive fluorescence 10 of greenish character, a lens for focusing the received beam upon said screen and an eye piece for observing said screen.
- In testimony whereof we affix our signatures in presence of two witnesses.
